UNITED STATES PATENT OFFICE.

AMANDA JENKINS, OF WINAMAC, INDIANA.

WINDOW SCREEN.

1,425,484.

Specification of Letters Patent. Patented Aug. 8, 1922.

Application filed March 21, 1921. Serial No. 454,089.

To all whom it may concern:

Be it known that I, AMANDA JENKINS, a citizen of the United States, residing at Winamac, in the county of Pulaski and State 5 of Indiana, have invented new and useful Improvements in Window Screens, of which the following is a specification.

This invention relates to screens for windows and has for its object the provision of 10 a screen which is normally rolled upon a spring roller and which is capable of being pulled down for use, the roller and screen when wound thereon being enclosed within a casing which will protect the screen and 15 greatly increase its life.

An important object is the provision of guides located at the sides of a window and within which the edges of the screen are disposed, braided strips being slidably disposed 20 within these guides and engaging within the mesh of the screen.

An additional object is the provision of means of this character which will be simple and inexpensive in construction and installation, highly efficient in use, durable in service, 25 and a general improvement in the art.

With the above and other objects and advantages in view, the invention consists in the details of construction to be hereinafter 30 more fully described and claimed and illustrated in the accompanying drawings in which—

Figure 1 is a front elevation of my screen showing it in extended position,

Figure 2 is a vertical cross sectional view 35 through one of the guides, and

Figure 3 is a cross sectional view.

Referring more particularly to the drawings, the letter A designates a window frame 40 having the usual sides B. In carrying out my invention I provide a guide member 10 secured upon each side B and this guide member is formed, for example, of sheet metal cut and bent to shape and is channel-shaped in cross section whereby to provide 45 an internal space 11 with which communicates a slot 12. On the inner side of one wall this guide is formed with a longitudinal groove 13 for a purpose to be described.

Secured transversely of the window frame 50 preferably at a height corresponding to the top of the lower sash, is a sheet metal housing 14 within which is journaled a sheet

roller 15 of conventional type upon which is wound the sheet 16 of screenwire, and this 55 sheet should be of such a width that its edges will be disposed within the guides 10. Any suitable handle 17 may be provided at the lower edge of the screen and this lower edge is also reinforced by a stiffening bar 18 60 of any desired construction.

Slidable within each of the guides 10 is a strip 19 from one side of which extend brads or pins 20 which are designed to pass through the mesh of the screen and these pins are 65 disposed within the grooves 13.

In the use of the device it will be seen that ordinarily, that is when the screen is rolled upon the roller, the strips 19 are in their uppermost position. When the window is open 70 and it is desired to place the screen in position, it is merely necessary that the operator grasp the handle 17 and pull downwardly thereon whereupon the screen will be unrolled from the roller 15. As the screen is 75 moved downwardly the engagement of the mesh with the pins or brads 20 will cause the strips 19 to slide downwardly within the guides 10. The function of the strips and guides is to hold the screen rigid so that it 80 cannot pull in or out.

From the foregoing description and a study of the drawings it will be apparent that I have thus provided a simply constructed and inexpensive screen which may 85 be easily installed and which may remain permanently upon the window and which will moreover be durable, especially in view of the fact that when not in use it is protected by the casing.

While I have shown and described the preferred embodiment of my invention, it is of course to be understood that I reserve the right to make such changes in the form, construction, and arrangement of parts as will 95 not depart from the spirit of the invention or the scope of the subjoined claim.

Having thus described my invention, I claim:

A window screen device comprising a casing 100 secured transversely of the window frame at the intermediate portion thereof, a spring roller within said casing, a sheet of wire screen secured to and adapted to be wound upon said roller, a pair of upright 105 channeled guide members located at oppo-

site sides of the window frame and extending throughout the lengths thereof, rigid strips slideable within said guide members and each carrying spaced pins arranged longitudinally thereof, the side edges of unwound portions of the screen extending into said guides with the mesh of the screen en-

gaged upon adjacent pins, said guides having their forward walls off-set to define grooves for the accommodation of the pins, 10 and a stiffening bar at the lower edge of the screen and provided with a handle.

In testimony whereof I affix my signature.
AMANDA JENKINS.
